(57) **CLAIM**

The ornamental design for the abrasive sharpener, as shown and described.

DESCRIPTION

FIG. 1 is a front perspective view of the ornamental design for abrasive sharpener of the invention;

FIG. 2 is a left elevational end view, viewing FIG. 1, of the ornamental design for abrasive sharpener of FIG. 1;

FIG. 3 is a front elevational view of the ornamental design for two abrasive sharpener of FIG. 1;

FIG. 4 is a back elevational view of the ornamental design for abrasive sharpener of FIG. 1;

FIG. 5 is a right end elevational view, viewing FIG. 1, of the ornamental design for abrasive sharpener of FIG. 1.

FIG. 6 is a top plan view of the ornamental design for abrasive sharpener of FIG. 1; and,

FIG. 7 is a bottom plan view of the ornamental design for abrasive sharpener of FIG. 1.

The broken lines define unclaimed portions of the design.
